UNITED STATES PATENT OFFICE.

JOHN VOLLMER, OF ESSEN, GERMANY.

GUN BARREL WITH BREECH PIECE SCREWED ON A-TUBES.

1,427,137.

Specification of Letters Patent. Patented Aug. 29, 1922.

Original application filed November 19, 1920, Serial No. 425,106. Divided and this application filed June 28, 1921. Serial No. 481,028.

To all whom it may concern:

Be it known that I, JOHN VOLLMER, residing at Essen, Germany, a citizen of the German Republic, have invented a certain new and useful Improvement in Gun Barrels with Breech Pieces Screwed on A-Tubes (for which I have filed an application in Germany June 2nd, 1921), of which the following is a specification.

10 This invention relates to gun barrels having a breech-piece screwed upon the A-tube. The object of the invention is to provide means for attaining a rigid connection between the A-tube and breech-piece.

15 This application is a division of my co-pending application Serial No. 425,106 filed November 19th, 1920.

This invention relates particularly to means for obtaining this desired rigid connection with a breech-piece which envelopes only a small portion of the A-tube. The various features of this invention will be made more apparent in the accompanying specification and drawings in which:

25 Fig. 1 is a longitudinal section of a gun barrel and breech-piece constructed in accordance with this invention,

Fig. 2 is a section on line 2—2 of Fig. 1,

Fig. 3 is a plan view partly in section of 30 the structure illustrated in Fig. 1, and

Fig. 4 is a section of a detail on a larger scale.

The gun barrel consists of an A-tube A and a breech-piece B, this breech-piece being 35 formed with a very short jacket portion b' which envelopes the rear portion of the A-tube. The breech-piece is provided on its under side with a lug for the attachment of a recoil brake and the running out gear. 40 The connection between the A-tube and the breech-piece is obtained by means of screw-threads a² b² on the A-tube and breech-piece respectively.

The jacket portion b' of the breech-piece 45 B is provided with an annular extension b⁴, having the same outside diameter as the collar a⁴ formed on the A-tube A. The collar a⁴ and the extension b⁴ are each provided on their opposite faces with six recesses a⁵ and b⁵. When the A-tube and breech-piece 50 are assembled, the wall of each pair of recesses a⁵ and b⁵ enclose a cylindrical hole or recess in which a cylindrical dowel F is inserted.

55 The dowels F (see more particularly Fig.

4) are made of soft expansible steel. Each dowel F is perforated by an oval slot f' extended from one end face f² to the other, the generatrix of the slot being parallel to the axis of the dowel. A double wedge formed by two wedges G G' is adapted to be driven into this slot. The dowels F and the wedges G G' are retained in position by a ring H fixed over the collar a⁴ and the extension b⁴ in any suitable manner, preferably by shrinking the same thereon.

The arrangement is applied in the following manner: After the breech-piece has been screwed on the A-tube the recesses a⁵ b⁵ are bored and the dowels F are placed in the recesses in such a manner that the oval slots f' of some of the dowels assume the position shown in the drawing whereas the oval slots of the remaining dowels are placed at right angles thereto. Then the wedges G G' are inserted in the dowels and driven tightly therein, thereby expanding the dowels and rigidly connecting the A-tube and the breech-piece. Finally the ring H is fixed over the collar a⁴ and the extension b⁴.

This alternate arrangement of the dowels F and the wedges G G' will prove a safeguard against the loosening of the breech-piece on the A-tube owing to the resistance set up by the recoil brake and the running out gear. It also prevents the loosening of the A-tube in the breech-piece, owing to the reaction of the rifling tending to rotate the A-tube. Furthermore, the cylindrical shape of the dowels F and the recesses a⁵ and b⁵ facilitates the exact machining of the parts in question and assures a uniform distribution of the pressure produced by the described wedge arrangement.

Having thus described my invention, what I claim is:

Claims:

1. A gun barrel comprising an A-tube, a breech-piece, said breech-piece being provided with an annular extension, said A-tube being provided with a collar, said annular extension and collar being opposed and shaped to receive a multiplicity of wedges.

2. A gun barrel comprising an A-tube, a breech-piece, said breech-piece being provided with an annular extension, said A-tube being provided with a collar, the opposed faces of the annular extension and collar being shaped to provide recesses and an

expanding means disposed in the hollow space formed by the opposed recesses.

3. A gun barrel comprising a breech-piece, an A-tube, said breech-piece being provided with an annular extension, said A-tube being formed with a collar, said annular extension and collar being disposed adjacent one another, the opposed faces thereof being shaped to form recesses and expansible dowels 10 adapted to be inserted in the spaces formed by the opposed recesses and wedges for expanding said dowels.

4. A gun barrel comprising an A-tube, a

breech-piece, said breech-piece being provided with an annular extension, said A-tube 15 being provided with a collar, the opposed faces of the annular extension and collar being shaped to provide recesses, expanding means disposed in the hollow space formed by the opposed recesses and a ring covering 20 said annular extension, collar and tension devices.

The foregoing specification signed at Es-
sen, Germany, this 24th day of May, 1921.

JOHN VOLLMER.
